UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

SHUTTLE FOR SIDE-MOTION-FEELER LOOMS.

1,344,066.

Specification of Letters Patent. Patented June 22, 1920.

Application filed February 21, 1920. Serial No. 360,320.

To all whom it may concern:

Be it known that I, EDWARD S. STIMPSON, a citizen of the United States, and resident of Hopedale, county of Worcester, State of Massachusetts, have invented an Improvement in Shuttles for Side-Motion-Feeler Looms, of which the following description, in connection with the accompanying drawing, is a specification, like characters on the drawing representing like parts.

This invention relates to improvements in shuttles for use in side motion feeler looms. In such types of looms, as is well known to those skilled in the art, a feeler is employed which, upon the beat-up of the lay, enters through a feeler slot in the wall of the shuttle and contacts with the mass of filling upon the filling carrier. The feeler mechanism is so constructed that when the running filling has reached a predetermined degree of exhaustion, or has become entirely exhausted, the feeler has a side motion usually due to it, or some portion of it, slipping upon the smooth surface of the filling carrier, and this side motion is utilized to effect the initiation of filling replenishment or other change in the operation of the loom.

In the operation of looms the shuttle is sometimes mispositioned by reason of slight rebounding from the picker stick, or because of its failure fully to enter the shuttle box at the feeling end of the loom and resulting in either case in bringing the path of the feeler nearer the butt end of the shuttle than the normal path of the feeler. This brings the feeler opposite the smooth outer wall of the shuttle or opposite one of the jaws which clamps the butt of the filling carrier in the shuttle. In such case the feeler engages either the smooth wall of the shuttle or the smooth surface of the shuttle jaw and a side motion takes place in the same manner as if it had engaged the smooth surface of a depleted filling carrier.

Patent No. 1,302,689, granted May 6, 1919, to T. F. Brazil, discloses, in broader claims, means for preventing premature action of a side motion of the feeler when the latter engages a misplaced shuttle. Its specific mechanism disclosed therein comprises serrations upon the outer wall of the shuttle jaw which is exposed by the feeler slot which extends through one of the walls of the shuttle.

Patent No. 1,303,583, granted May 13,

1919, to Osgood, discloses a shuttle in which the feeler slot does not extend along the shuttle jaws, but in which a series of vertical serrations are provided in the outer wall of the shuttle immediately beyond the 60 end of the feeler slot and opposite the shuttle jaws, these serrations being adapted to engage the feeler and prevent premature operation thereof when the shuttle is longitudinally misplaced in the shuttle box. 65

The present invention contemplates the provision of a simple means by which a usual form of shuttle may be provided with means for preventing premature action of a side motion feeler when the shuttle is misplaced without the necessity of a special construction either of the shuttle body or of the shuttle jaws. This is accomplished by providing means within the feeler slot, located outside of the normal field of operation of 75 the feeler, which are adapted to engage the feeler if the shuttle is misplaced longitudinally, and prevent improper actuation thereof, said means being so constructed as to be readily applied to a usual type of shuttle. 80

A further object of the invention is to provide the shuttle with means for preventing improper operation of the side motion feeler which can be readily assembled in usual types of shuttles and which can be 85 readily removed and replaced.

Other objects and features of the invention will more fully appear from the following description and the accompanying drawings and will be pointed out in the annexed 90 claims.

In the drawings, which represent a preferred embodiment of the invention,

Figure 1 is a side elevation of the end of the shuttle having my invention embodied 95 therein.

Fig. 2 is a plan view of the end portion of the shuttle showing the shuttle jaws clamping a filling carrier therein and illustrating the means for preventing improper 100 operation of the side motion feeler.

It will be obvious from the statements heretofore made that the construction and operation of the loom and of the side motion feeler mechanism is unaffected by the 105 present invention which has only to do with the construction of the shuttle itself. Consequently the description herein is restricted to the shuttle.

In its general construction the shuttle may 110

- be of any usual type. As illustrated herein the body 1 of the shuttle is provided with the usual longitudinal recess 2 extending through the shuttle from top to bottom to receive the filling carrier 3 which, as indicated in dotted lines, may be a wooden bobbin of the usual type having an enlarged base provided with rings 4 which are grasped between the shuttle jaws 5 and 6.
- 10 The front wall 7 of the shuttle is provided with a longitudinal feeler slot 8 the walls of which are in parallelism with the bottom and top of the shuttle. The slot 8, in usual shuttle construction, extends toward the end 15 of the shuttle beyond the jaw 6.

In the normal operation of the loom the feeler is inserted during the beat-up of the lay through the feeler slot opposite to the smooth barrel of the filling carrier and if it 20 encounters a mass of filling upon said filling carrier is prevented from side-wise movement. When, however, the filling is depleted, the feeler engages the smooth surface of the barrel of the filling carrier and slips 25 longitudinally thereon, thereby effecting an initiation of mechanism which produces a change in the operation of the loom. If the shuttle becomes improperly placed at the time the feeling action occurs, the feeler is 30 likely to engage the outer smooth face of the shuttle jaw 6 in which case the feeler will slip side-wise and effect a change in the operation of the loom just as if it had engaged the smooth barrel of the filling carrier.

35 The present invention consists in introducing into the feeler slot means which will prevent the side-wise movement of the feeler, the means thus introduced being of such a character that it will not wear rapidly and 40 preferably being so secured as to be readily removed and replaced.

A most simple expedient, which is illustrated in the drawing, comprises a pin, preferably a plurality of pins 9 and 10 spaced apart a considerable distance, which are inserted vertically through the wall 7 of the shuttle across the feeler slot 8 outside or beyond the normal field of operation of the feeler.

45 As shown herein the pins 9 and 10 are both located opposite the jaw 6 of the shuttle and serve to engage the feeler if the shuttle is sufficiently misplaced to place the pins 9 or 10 in the path thereof. Any number of pins 50 9 and 10 may be employed and spaced apart any desired distance as required by the particular kind of shuttle which is employed.

The pins 9 and 10 desirably are of sufficiently small diameter to enter into the recess or serrations in the end of the feeler and thereby lock it against side-wise movement during the beat-up of the lay. As illustrated herein these pins are shown as driven vertically downward through the wall 7 of 55 the shuttle transversely across the feeler

slot 8. Thus they are easily applied to any usual type of shuttle and are capable of being readily removed and replaced when worn or broken. The presence of these pins in the wall of the shuttle will not interfere 70 with the use of the shuttle in looms having other types of feelers or in non-automatic looms. The shuttles, therefore, may be equipped with this invention without danger of interference with other uses of the 75 shuttles than in the side motion feeler automatic filling replenishing loom. The embodiment of my invention in usual shuttles may also be made without any material expense and without the necessity either of 80 special construction of the shuttle body or of the shuttle jaws. In fact, my invention can be incorporated into an ordinary shuttle without difficulty thereby providing a ready supply of shuttles for a side motion feeler 85 loom which will readily and effectively insure the proper operation of the feeler mechanism notwithstanding the misplacement of the shuttle.

It will be understood that various modifications in form, construction and arrangement of parts may be made within the spirit and scope of the following claims.

Having thus described my invention, what I claim as new and desire to secure by 95 Letters Patent, is:

1. A shuttle for use in side motion feeler looms provided with a filling carrier recess and means to clamp and hold the filling carrier therein, one wall of said shuttle having 100 a feeler slot to permit the passage of the feeler therethrough, means located within said feeler slot out of the normal field of operation of the feeler adapted to engage the feeler, if the shuttle is longitudinally 105 misplaced at the time of feeling and prevent premature actuation of said feeler.

2. A shuttle for use in side motion feeler looms provided with a filling carrier recess and means to clamp and hold the filling carrier therein, one wall of said shuttle having 110 a feeler slot to permit the passage of the feeler therethrough, a metallic member fixedly secured within the feeler slot in said shuttle wall outside of the normal field of 115 operation of the feeler adapted to engage the feeler, if the shuttle is longitudinally misplaced at the time of feeling and prevent side motion of said feeler.

3. A shuttle for use in side motion feeler 120 looms provided with a filling carrier recess and means to clamp and hold the filling carrier therein, one wall of said shuttle having a feeler slot to permit the passage of the feeler therethrough, a metallic pin anchored 125 in the shuttle wall and extending into the feeler slot in the shuttle outside of the normal field of operation of the feeler adapted to engage the feeler, if the shuttle is longitudinally misplaced at the time of feeling 130

and prevent premature actuation of the feeler.

4. A shuttle for use in side motion feeler looms provided with a filling carrier recess 5 and means to clamp and hold the filling carrier therein, one wall of said shuttle having a feeler slot to permit the passage of the feeler therethrough, a plurality of pins spaced apart and seated in the wall of the

shuttle extending transversely across the 10
feeling slot outside of the normal field of op-
eration of the feeler and adapted to engage
the feeler, if the shuttle is longitudinally
misplaced at the time of feeling, and prevent
premature actuation of said feeler. 15

In testimony whereof, I have signed my
name to this specification.

EDWARD S. STIMPSON.
